UNITED STATES PATENT OFFICE.

OTTO J. LAUTERBACH, OF NEW ORLEANS, LOUISIANA.

INK-SAVING DEVICE FOR COTTON-PRINTING MACHINES.

Application filed August 11, 1921. Serial No. 491,473.

To all whom it may concern:

Be it known that I, OTTO J. LAUTERBACH, a citizen of the United States, residing at New Orleans, in the parish of Orleans and 5 State of Louisiana, have invented certain new and useful Improvements in Ink-Saving Devices for Cotton-Printing Machines; and I do declare the following to be a full, clear, and exact description of the invention, 10 such as will enable others skilled in the art to which it appertains to make and use the same.

This invention relates to an improved scraper for use in connection with the ink-well of a cotton printing press and one object of the invention is to provide a scraper so constructed that it may be connected with the ink-well and positioned in operative relation to the feed roller and serve to scrape 15 lint, thick ink and other matter off of the feed roller and thus prevent the lint and other matter from working back into the ink placed in the ink-well. In presses for printing cotton, burlap and other fabric, the 20 inking rollers gather lint from the fabric and this lint is passed from one roller to another until it finally reaches the inking roller which serves to feed ink out of the ink-well. When this lint becomes mixed 25 with the ink in the ink-well, the ink in the ink-well is spoiled and the ink-well becomes choked so that the ink will not properly feed out of the ink-well. By providing the improved scraper, the lint can be scraped off 30 of the roller and thus the ink in the well be kept clean and prevented from being spoiled.

Another object of the invention is to provide a scraper which can be easily connected 40 with the side walls of an ink-well above the feeding roller with the scraping blade extending downwardly and engaging the feeding roller.

Another object of the invention is to provide a scraper which will have a very simple construction and which can be cheaply produced and easily put in place.

This invention is illustrated in the accompanying drawings, wherein:

Figure 1 is a perspective view showing 50 the scraper in use.

Figure 2 is a transverse sectional view through the scraper and feeding roller of an ink-well.

Figure 3 is a perspective view of the im- 55 proved scraper.

This scraper is to be used in connection with the ink-well 1 of a cotton printing press and is intended to scrape lint from the ink feeding roller 2. As previously ex- 60 plained, this lint is taken from the cotton which is being printed and is transferred across a series of rollers to the roller 2. One of these rollers is shown and indicated by the numeral 3. The press structure has 65 not been shown since the invention is only applied to the ink-well 1 and the device can be used in connection with any ink-well having side walls 4 between which will be rotatably mounted the ink feeding roller 70 2. This scraper is provided with a carrier bar 5 which extends across the ink-well above the roller 2 and has its end portions provided with openings 6 to receive fastener bolts 7 which serve to secure the car- 75 rier bar in place upon the ink-well. A scraping blade 8 which is preferably formed of sheet metal extends below the carrier bar 5 as shown clearly in Figs. 2 and 3 and as shown in Fig. 2 has its free edge en- 80 gaging the face of the roller 2. From an inspection of this Fig. 2, it will be readily seen that as the roller turns in the direction indicated by the arrow, the scraper blade 85 8 will serve to scrape the surface of the roller and effectively remove from this roller any lint, thick ink or other matter which may have accumulated upon the roller. By having the carrier bar 5 secured by bolts 90 7, these bolts may be removed and the scraper thus easily and quickly removed when it is desired to clean or repair the same. It will be further noted that with the construction shown, the scraper blade 8

can be easily removed and a new one put in place when necessary. It will also be noted that the scraper is so constructed that it can be readily applied to an ink well of a conventional construction and therefore can be readily applied to ink-wells already installed.

I claim:

The combination with an ink-well having 10 side walls, and a feeding roller rotatably mounted between the side walls, of a lint

remover having a carrier bar removably secured upon the side walls and extending across the ink well and a vertically disposed scraper blade formed separate from said bar and secured to one side of the carrier bar and extending beneath the carrier bar for engaging the face of the feeding roller. 15

In testimony whereof I have hereunto set my hand.

OTTO J. LAUTERBACH.
